UNITED STATES PATENT OFFICE.

ERNEST WEBBER RICHMOND, OF DURSLEY, ENGLAND, ASSIGNOR TO R. A. LISTER AND COMPANY LIMITED, OF DURSLEY, ENGLAND.

CENTRIFUGAL LIQUID-SEPARATOR.

No. 894,855.

Specification of Letters Patent.

Patented Aug. 4, 1908.

Application filed May 10, 1907. Serial No. 372,873.

To all whom it may concern:

Be it known that I, ERNEST WEBBER RICHMOND, a subject of the King of Great Britain, residing at Prospect House, Dursley, in the county of Gloucester, England, mechanical engineer, have invented certain new and useful Improvements in Centrifugal Liquid-Separators, of which the following is a specification.

10 This invention refers to improvements in separators, and has for its object the provision of effective means for the conveyance of the heavier liquid which collects near the walls of the separator bowl to the top where 15 the passages out of the bowl are provided.

The invention is particularly intended for cream separators and consists in the provision of a skimming shield, adapted for sitting over the separating cones, disks, liner 20 plates, or the like, under the coned cover of the separator bowl, and providing the necessary passages to the top of the bowl. The skimming shield has provision for being firmly held in place and communicates with 25 the lower part of the bowl over the separating means.

The preferred manner of carrying out the invention is to construct the skimming shield of conical shape from pressed steel or other 30 suitable material and to provide it with a neck either integral with it or secured thereto. The skimming shield is pressed with a plurality of grooves on its sides extending from the bottom to the upper part where the neck 35 commences. These grooves are arranged at regular intervals in the sides of the skimming shield, a convenient number for ordinary uses being four. The neck of the skimming shield is for the purpose of securing its shield in 40 position and for the conveyance of the cream from the center of the bowl, and may be either pressed in one therewith or be separately formed and secured thereto. It has one, two, or more snugs or projections on its 45 exterior adapted when the skimming shield is in position to engage one or more radial inclined pieces standing proud of the top of the coned or outer cover of the bowl. In securing the said shield in position it is placed 50 over the separating means in the separator bowl and its neck projects through a central aperture formed in the cover of the bowl, the lugs on the neck passing through slots in the cover provided to take them; the neck 55 is then given a partial turn so as to cause the

snugs or projections to ride upon the inclined planes tightly locking the skimming shield against the cover. When in this position, the grooves in the sides of the shield acting in conjunction with the interior of the cover, 60 form complete tubes up which the skim milk passes from around the walls of the bowl to the top of the cover where the slots in the cover for passing the locking snugs on the skimming shield form exits for it. The neck 65 as will be seen also forms a tube for the conveyance out of the bowl of the cream which accumulates at the center.

As a modification I may form the passages on the exterior of the skimming shield, by 70 securing gutters thereon instead of pressing the grooves in, or I may press up parallel ribs on the exterior to form troughs, and either of these methods provide complete tubes when the shield is locked in position beneath the 75 top.

On the explanatory drawings appended hereunto:—Figure 1 shows a section through a separator bowl with the cover on and my invention applied thereto. Fig. 2 is a plan 80 of same. Fig. 3 is a sectional elevation of the skimming shield. Fig. 4 is a plan of skimming shield. Fig. 5 is a sectional elevation of the upper part of the skimming shield, at right angles to Fig. 3. Fig. 6 is a side view 85 of the cover of the separator bowl. Fig. 7 is a vertical section, and Fig. 8 is a plan of same. Fig. 9 is an elevation of a modification of the skimming shield. Fig. 10 is a plan. Fig. 11 is a section of the same taken 90 at line c—d of Fig. 9, and Fig. 12 is a partial sectional view of the cover and skimming shield showing the means whereby the latter is drawn tightly against the inner contour of the former.

95 On the drawings, B is the separator bowl, and C is the conical cover while the separating means are shown as cones and represented by D.

The skimming shield is indicated by T. 100 At Figs. 3, 4 and 5, the shield is shown in its preferred form. It is pressed from sheet metal and given the shape of a truncated cone. The walls are formed with grooves t^1 pressed in their outer surfaces extending 105 from the bottom edge to the point where the cone shape finishes in a flat shoulder t^2 . Integral with the cone shaped part a neck N is pressed which is provided with a strengthening lining n^1 and with the snugs or projec- 110

tions n^2 . The cover C of the bowl is similarly of truncated cone shape and has a central aperture c^1 at the top. On each side of the aperture an inclined faced projection c^2 is formed as clearly seen at Figs. 6, 7, and 8. The projections or snugs n^2 on the neck N of the skimming shield, pass slots c^3 in the cover C, as the neck is passed through the central aperture when the shield and the cover are placed in position, and are adapted to ride up the gradients c^2 and secure the skimming shield tight against the cover when the neck is partially rotated.

When the skimming shield T is in proper position in the bowl as seen at Fig. 1, the groove t^4 pressed in its outer surfaces in conjunction with the inner faces of the cover C forms complete tubes for the conveyance of the heavier liquids from the sides of the bowl where it accumulates to the top, where it passes out through the slots c^3 in the cover. In this way provision is made which effects the ready clearance of the skim milk from the bowl and greatly facilitates the work of separation.

In the modification shown at Figs. 9 to 11, the passages for the skim milk on the skimming shield T are formed by soldering or otherwise securing troughs or parallel ribs t^5 on the exterior. The part T has a flange t^6 round the lower edge, which is cut away where the troughs commence to form an entry to the same. The shield in this case is arranged in the bowl in the same way and acts in a similar manner.

What I claim is:

1. In a liquid separator, a bowl, a cover therefor having an opening in its upper part,

and with inclined projections upon said upper part, a skimming shield within said cover and having a neck extending outwardly through the opening aforesaid and provided with snugs, which engage the inclined projections aforesaid, for tightening the skimming shield in place.

2. In a liquid separator having a bowl, a number of liner plates and a cover, an opening in the upper part of said cover, inclined projections upon said upper part and around said opening, and a separable grooved skimming shield within said cover with a neck extending through the said opening in said cover, and snugs on the said neck adapted to engage said inclined projections on said cover to draw the skimming shield tight against the inside thereof.

3. In a liquid separator having a bowl, a number of liner plates, and a cover, the combination of a cover having inclines on its upper part with a skimming shield having a pair of snugs for engaging said inclines, the said shield further having grooves up its sides.

4. In a liquid separator, a bowl, a number of liner plates, a cover, a skimming shield having milk grooves, and a fastening device, between said cover and said skimming shield, comprising snugs and inclines.

In testimony whereof, I have signed my name to this specification in the presence of two subscribing witnesses.

ERNEST WEBBER RICHMOND.
